(57) **CLAIM**

The ornamental design for a pitcher with light ring substantially as shown and described.

DESCRIPTION

FIG. 1 is a perspective view of an embodiment of a pitcher with light ring showing our new design;

FIG. 2 is a front elevation view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines shown in the drawings depict portions of the pitcher with light ring that form no part of the claimed design. The non-parallel dashed lines emanating from the light ring shown in the drawings depict environmental
